LIFTING JACK

Frank P. Hallor, Peoria, Ill.

Application July 8, 1946, Serial No. 681,893

8 Claims. (Cl. 254—111)

1

This invention relates to lifting-jacks employing a pair of pawls used for both load lifting and load lowering purposes.

An important object of the invention is to provide means which, when a load on the jack is being let down, the pawls may be individually controlled in a wholly positive manner to thereby prevent falling of such load as often results in the use of such jacks.

Further, an object is to provide means at each pawl so that the jack may be operated in a positive and safe manner without the necessity of the operator adjusting or having to touch either pawl to make sure of safe lowering operations.

Still another object is to automatically and separately control each of the two pawls of a jack, looking to safe lowering of a load, so that the operator need devote his entire time and attention to the operating hand-lever only and the effects upon the load being handled.

Other objects and advantages will appear herein as the description proceeds aided by the appended drawing forming part hereof, and wherein

Figure 1 is a side elevation of a part of a common form of jack which includes therein the parts of my invention.

Figure 2 is a plan of the jack according to my invention, said jack being shown in horizontal section on line 2, 2 of Figure 1.

Figure 3 is a side elevation of the same wherein the parts of the invention are shown in different positions from those shown in Figure 1.

Figure 4 is a transverse section of a forked portion of the hand-lever of the jack and a manner of mounting thereon a swingable member shown in the foregoing figures.

Figure 5 is a longitudinal section of a swingable member shown in Figure 4, produced in a larger scale.

Figure 6 is a detail in elevation of parts shown in the foregoing figures, and

Figure 7 is an enlarged plan of a member shown in the earlier figures, together with a rod portion to engage therein.

The mechanism of the invention is adaptable to certain forms of jacks of the type named herein, while also adapted to be mounted upon certain of such forms to render them more readily and safety operated, especially when a load carried by the jack is in process of being lowered.

In the described figures A denotes the frame, base, or standard of a jack, and B the ratchet bar common to this particular type, said bar being guided slidably in a vertical direction with-

- in a channel C of said frame or base, the ratchet teeth D in this instance being exposed above the said frame for pawl engagement, as well as at a recess E in such frame also for pawl engagement. Also, extending from the frame forwardly at each side of the ratchet bar B is a lug or ear F, Figure 2, which jointly support pivotally, by a bolt G, the forked end H of a hand lever J. As parts of said forked end is a pair of arms K, each being spaced outwardly from each extension of the fork, both said extensions and said arms may be substantially coextensive in length. Pivotally hung from between each lever-extension and its adjacent arm is an arm of a lifting pawl L having the usual form of a U whose depending yoke portion is adapted for engaging a tooth of the said ratchet-bar within the recess E. Again a load supporting pawl M is mounted to swing on the named bolt G in position to engage the teeth of the ratchet-bar, a spring N secured at one end to the frame and having a position to bear at its other end on the pawl M to urge the same in the direction of said teeth.
- Such a structure is more or less common to jacks and has merely been outlined for the purpose of aiding the understanding of the manner of placing and mounting of the combined mechanism as an operating whole.
- The parts included in the invention to cooperate with parts of the above described structure may now be understood. That is to say, pivotally connected in any desired manner to the pawl M is one end of a rod I which extends at its other end along the hand lever J, there being, in this instance, a helically wound spring 2 slidable along the rod, the latter terminating in abutment 3.
- Affixed to the hand lever distant from the pawl M is a member 4 having a notch 4' in its top, providing a fork, wherein the rod may lie and within which, also, said rod may freely shift in the raising and lowering movements of said hand lever.
- Suitably affixed to one of the arms of the described lifting pawl L, near its place of pivotal suspension, is a finger 5 which, in the present instance extends upwardly and forwardly from said pawl, said finger 5, since a part of the pawl, having a certain office to be made known.
- Finally, pivoted on the hand lever near the pivotal mounting of that member is a tubular stem 6, shown best in Figures 4 and 5.
- In said Figure 4 this stem may be pivotally supported at said lever to swing in a vertical

plane, forwardly and rearwardly, as will be understood by comparing Figures 1 and 3, its plane of swing lying in the line with the position of the finger 5 as shown in Figure 2, and the free end of said stem may lie below said finger as in Figure 3.

This stem is tubular and receives slidably into it a pin 7 compressed beneath which, within said stem, is a spring 8, a pin or bolt 9 held in said pin 7 extending through a slot 10 of the stem limiting the outward movement of said pin 7.

While all this structure described as applied to the jack parts answer the purpose for which they are intended it is, of course, possible to otherwise construct them to at the same time answer the said purpose.

In the position of the new structural parts shown in Figure 1 the jack in operation answers for lifting purposes as in any jack of a like type, there being no control of the weight holding pawl M nor control of the lifting pawl L by said new structure, the only control being the usual spring N for said pawl M, and the force of gravity for the said lifting pawl L. That these pawls may be free to function normally in lifting operations, the stem 6 is in a forward or neutral position where in the operation of the hand lever it will not move into the vicinity of nor have contact with the finger 5. Likewise in Figure 1 the rod 1 is free to slide within the member 4 the spring 2 having no office in the position shown since in an inoperative position clear of any parts.

When, however, a sustained load is to be lowered and the hand lever is in a raised position, or even in the positions shown in Figures 1 and 6, the rod 1 may be lifted free of the member 4. Then by shifting the spring 2 along said rod one end may lie against the abutment 3 while the other end may be made to abut member 4 when the rod is replaced in that member.

At the time the lever is lowered the spring will be compressed as the member 4 moves further away from the pawl. Thus the spring serves to withdraw the pawl M from tooth engagement.

Also, the stem 6 is swung from the position shown in Figure 1 toward and beneath the finger 5 of the lifting pawl 1 to engage the same as the lever rises.

Having performed these acts the action of the jack is as follows:

When the lever is lifted the pawl M is allowed to move into tooth engagement due to the movement of the rod 1 toward the ratchet bar, the spring N of that pawl now taking control, said pawl now, of course, engaging a tooth to support the load. In the said lift of the lever, also, the pin 7 is moved up to and abuts the under surface of the finger 5. In the continued upward lever movement the spring 8 beneath the said pin 7 is compressed from the fact that the pawl L, of which the finger is a part, is momentarily fixed and held in supporting the load. A completion of lever movement relieves the weight on said pawl L, the pawl M now holding the load, whereupon the reflex action of said spring 2 swings said pawl L clear of the ratchet bar. Since gravity now controls the pawl L, that member after its release, will drop into engagement with a ratchet bar tooth in a succeeding upward movement of the hand lever.

In lowering of the hand lever the pawl M is withdrawn from a tooth as before noted and is held away from the ratchet bar by said rod 1 and

its spring 2, the pawl L which is in engagement with a tooth naturally being raised due to its connection with the lever at the forked end thereof.

It is now believed to be clear that the described structure involved in this invention automatically and positively controls both pawls L and M in the lowering of the ratchet bar, the pawl L being withdrawn for engagement while the pawl M is in engagement. Also that when the latter is disengaged the former is engaged. Thereby the operator is free to manipulate the hand lever without giving manual attention as heretofore required in respect to said pawls in a jack of the type considered herein.

I claim:

1. In a lifting jack including a base portion, a ratchet bar, a gravity operated lifting pawl, a spring operated holding pawl, and a hand lever, in combination, a rod operatively connected to the spring operated holding pawl and provided with an abutment, a part carried by the hand lever to swing about the lever-fulcrum to slidably receive the rod, a spring on said rod adapted to lie between the abutment and said part and abutting both, the lowering movement of said lever adapted through said spring to withdraw said pawl from engagement with the ratchet bar, and in the raised position of said lever said pawl being free to engage said ratchet bar, an extension having a fixed position on the lifting pawl, a part mounted on the hand lever adapted to be moved to two different positions thereon, said part in one position lying adjacent the extension and lying distant therefrom in the other position, and said part when in the first named position adapted in a lifting movement of the hand lever to abut said extension and move the same to swing said lifting pawl away from the ratchet bar.
2. In a lifting jack including a base portion, a ratchet bar, a gravity operated lifting pawl, a spring operated holding pawl, and a hand lever, in combination, a rod operatively connected to the spring operated holding pawl and provided with an abutment, a part carried by the hand lever to swing about the lever-fulcrum, a part on said lever to slidably receive the rod, a spring on said rod and engageable with the said abutment and said part adapted in the lowering movement of said lever to withdraw said pawl free from engagement with the ratchet bar, the raising movement of the said lever releasing the tension of said spring to allow said pawl to engage said ratchet bar, an extension having a fixed position on the lifting pawl, a part mounted on the hand lever adapted to be moved to two different positions thereon, said part in one position lying adjacent the extension and lying distant therefrom in the other position, and said part when in the first named position adapted in a lifting movement of the hand lever to elastically abut said extension and move the same to swing said lifting pawl away from the ratchet bar.
3. In a lifting jack including a base portion, a ratchet bar, a gravity operated lifting pawl, a spring operated holding pawl, and a hand lever, in combination, a rod operatively connected to the spring operated holding pawl and having an abutment, a part carried by the hand lever to swing about the lever-fulcrum, a part on the lever with which the rod is engageable, a spring arranged to have two different positions on the rod, and in one position lying between the abut-

ment and said part, and adapted in the lowering movement of said lever to assist in withdrawing said pawl from engagement with the ratchet bar, and in the raised position of said lever said pawl being free to engage said ratchet bar, an extension having a fixed position on the lifting pawl, a part mounted on the hand lever adapted to be moved to two different positions thereon, an elastically controlled pin carried by the part, said part in one position lying adjacent the extension and lying distant therefrom in the other position, and said pin in said part when in the first named position adapted in a lifting movement of the hand lever to abut said extension and move the same to swing said lifting pawl away from the ratchet bar.

4. In a lifting jack, the combination with the base portion thereof, a ratchet bar, a gravity operated lifting pawl, a spring actuated holding pawl, and a hand lever controlling said lifting pawl, of a rod pivotally connected to the holding pawl and including an abutment, a part carried by the hand lever at a position thereon between its fulcrum and its operated end, a spring engageable with both the said abutment and said part adapted by compression thereof in the lowering movement of the lever to bring about the withdrawal of said holding pawl from the ratchet bar, said spring being disengageable from the abutment and part at another period in the movement of the lever, an extension fixed with respect to the said lifting pawl, a second part on the hand lever adapted to swing toward and from said extension, a portion carried by the said second part adapted to elastically engage the said extension when said part is adjacent the same, said portion acting to swing the said lifting pawl away from the ratchet bar when the said hand lever is raised.

5. In a lifting jack, the combination with the base portion thereof, a ratchet bar, a gravity operated lifting pawl, a spring actuated holding pawl, and a hand lever controlling said lifting pawl, of a rod operatively connected to said holding pawl and including an abutment, a part carried on the hand lever with which said rod may be at times operatively controlled, a spring on said rod to be selectively placed between the abutment and the said part or removed from both, and when in the first named position assisting in swinging said holding pawl away from the ratchet bar in opposition to the spring of said pawl during the movement of said lever, a part pivotally mounted on the lever adapted to be manually swung toward and away from the lifting pawl, and an extension on the latter in position to receive the part elastically against it to swing said lifting pawl away from said ratchet bar.

6. In a lifting jack, the combination with the base portion thereof, a ratchet bar, a gravity operated lifting pawl, a spring actuated holding pawl, and a hand lever pivotally carrying said lifting pawl, of a rod pivotally connected to the

holding pawl and extending along the hand lever toward its free end, said rod having an abutment remote from said pawl, a part fixed on the lever at a position between said pawl and the said abutment, a member on the rod insertable between the said part and said abutment to provide an elastic control of the pawl in a movement of the hand lever in one direction, said member being normally free of the 5 said part and said abutment, an extension on the lifting pawl fixed with respect thereto and lying at that side of the pivot thereof most distant from the part that engages the ratchet bar, a stem pivoted on the lever adapted to swing 10 and in one of its positions lying beneath said extension, said stem having a part to elastically abut said extension in the lifting movement of said lever, the elastically abutting part adapted to swing the lifting pawl free of the ratchet bar 15 when said pawl is relieved of weight thereon.

7. In a lifting jack, the combination with the base portion thereof, a ratchet bar, a gravity operated lifting pawl, a spring actuated holding pawl, and a hand lever controlling said lifting pawl, of a rod connected to said holding pawl, a part carried on the hand lever with which the rod may be operatively connected to selectively swing said holding pawl away from the ratchet bar in opposition to the spring of said pawl, an 25 extension on the lifting pawl which when raised will swing said pawl away from the ratchet bar, and a part on the lever normally spaced from said extension, said part adapted when moved beneath the latter to elastically engage and lift it 30 in a lifting movement of said lever.

8. In a lifting jack, the combination with its base and ratchet bar, a gravity operated lifting pawl, a holding pawl, and a hand lever, of a rod pivotally connected to the holding pawl and 35 including an abutment, a forked part carried by the hand lever wherein the rod may lie but liftable therefrom, a coil spring shiftable along the rod adapted in one position to lie between the said abutment and the said part during the 40 lowering movement of the ratchet bar, and in another position thereof removed from between said abutment and said part during the raising movement of the ratchet bar, an extension on the lifting pawl which when raised will swing 45 said pawl away from the ratchet bar, and a part on the lever normally spaced from said extension, said part adapted when moved beneath the latter by said lever to elastically engage and lift it in the lifting action of said lever.
